UNITED STATES PATENT OFFICE.

FITZ A. KIRBY, OF WYANDOTTE, MICHIGAN.

SMOKE-CONSUMING FURNACE AND DAMPER-REGULATOR THEREFOR.

SPECIFICATION forming part of Letters Patent No. 729,188, dated May 26, 1903.

Application filed September 13, 1902. Serial No. 123,276. (No model.)

To all whom it may concern:

Be it known that I, FITZ A. KIRBY, a citizen of the United States, residing at Wyandotte, county of Wayne, State of Michigan, have invented a certain new and useful Improvement in Smoke-Consuming Furnaces and Damper-Regulators Therefor, of which the following is a specification, reference being had to the accompanying drawings, which form a part of this specification.

My invention has for its object certain new and useful improvements in a smoke-consuming furnace and damper-regulator therefor; and it consists of the construction, combination, and arrangement of devices hereinafter described and claimed, and illustrated in the accompanying drawings, in which—

Figure 1 is a view in perspective showing parts broken away. Fig. 2 is a detail view of the water-column in vertical section and in elevation. Fig. 3 is a vertical cross-section. Fig. 4 is a vertical longitudinal section on the line 4 4, Fig. 3. Fig. 5 is a detail view of the damper in vertical section.

The purpose of my invention is to provide means for effecting perfect combustion in a furnace which shall be simple and inexpensive in application and which may readily be adjusted or applied to any furnace, at the same time effecting a great saving of fuel.

I carry out my invention as follows:

In the drawings, *a* is a boiler-furnace, *b* being a combustion-chamber; *c*, the grate; *d*, the ash-pit, and *e* the customary draft-doors into the ash-pit. At the rear of the grate is a bridge-wall *f*, formed with flues *g*, preferably arched thereover, as indicated at *h*. The bridge-wall is cut away over the arches, forming a chamber *i*, the rear of the bridge-wall extending upward into contact with the boiler, as indicated at *j*. By recessing the upper portion of the bridge-wall the heat from the combustion-chamber is permitted to be concentrated in the chamber *i*, underneath the boiler, preventing any undue cooling of the boiler. At the same time the extension of the rear portion of the bridge-wall upward into contact with the boiler prevents the passage of the products of combustion through the chamber *i*; the upper portion of the bridge-wall obstructing the passage of the products of combustion and deflecting

them back into the combustion-chamber and through the flues *g*. Said flues being restricted in their dimensions, the products of combustion are held in the flame of the combustion-chamber, whereby more perfect combustion is secured, while at the same time I provide means for supplying an increased amount of oxygen to the combustion-chamber to further assist in securing perfect combustion. To this end I provide damper-regulating devices consisting, essentially, of one or more dampers *k*. The dampers consist of drop-doors jointedly supported at their upper edges, as indicated at *l*. I prefer to locate the dampers over the customary fire-doors, (indicated at *m*), which doors *m*, however, I perforate, as indicated in the accompanying drawings, and over which and about which I place a frame *n*, said frame preferably having an inclined face for the drop-door or damper *k* to rest upon, the damper dropping down in closed position over the customary door *m*. Obviously a proper manipulation of the damper will assist perfect combustion within the combustion-chamber. The damper is actuated by a water-column *p*, supplied with water from any suitable source of supply, as from a water-pipe *q*, provided with a controlling-valve *r*. The water-column is provided with a piston *s*, having a piston-rod *t*, having an arm *u*, with which are connected two pulley-blocks *v v*, additional pulley-blocks *w w* being located at the base of the column, corresponding sets of pulley-blocks being connected by chains or cables *x x*, led over the pulley-blocks in a suitable manner and thence into proximity to the dampers, the cables or chains being led over pulleys *y y* to a connecting-bar *z* and thence over pulleys *o o*.

It will be seen that the arm of the piston-rod is held up by the water supplied to the column. The dampers are closed by wasting the water-supply within the column through a petcock (indicated by the numeral 1) in a waste-pipe *2*. The wasting of the water from the column permits the arm or cross-head *u* to descend, which in turn lowers the dampers. The provision of double pulley-blocks *v v* and *w w* at the top and bottom of the column gives a proper arrangement of the corresponding chains or cables—a travel of four to one

for the ends of the chains or cables taking hold of the dampers—whereby one falling of the water-column may last for a considerable period, the manipulation of the dampers depending, of course, upon the size of the column. Thus I may readily provide in a water-column where the piston has a five-foot stroke twenty feet of travel for the ends of the chains which engage the dampers. The opening of the petcock may be so slight that it may be kept open until the water is exhausted from the column. The ends of the chains engaging the dampers are preferably made so as to furnish a sufficient supply of air. The door then begins slowly to descend, the idea being to have the door slowly closing continuously, the door reaching a closed position, preferably, a little before it is time to fire up again. By providing means for automatically closing the dampers the damper-regulator becomes a great fuel-saver. Thus the construction of the bridge-wall at the rear of the combustion-chamber retards the draft and the passage of the products of combustion, holding the unconsumed gases, carbon, &c., for a longer period in the combustion-chamber to be commingled with the air supplied through the dampers. At the same time the natural draft is employed, as in ordinary furnaces, under and through the grates or through the draft-doors *e* or analogous devices.

Obviously any desired number of chains or cables may be connected with the bar *z*. When the chains are disengaged from the dampers, their adjacent extremities may be coiled up before the furnace, as indicated at 3. Thus in a damper-regulator of this description one

water-column may serve for any desired number of dampers.

The operation of my invention will now be understood, and it will be readily seen that there is nothing in the construction to get out of order.

By making the closing of the dampers automatic I am not dependent upon the attention of a fireman to prevent undue waste of fuel.

What I claim as my invention is—

1. In a furnace the combination of a damper, a water-column, means to control the waste of the water from said column, a piston supported by the water in said column, pulley-blocks supported upon said piston, pulley-blocks at the base of said column, and means connected with said damper and said pulley-blocks to control the closing of the damper.

2. In a furnace the combination of a damper, a water-column, means to control the waste of water from said column, a piston supported by the water in said column provided with a cross-arm, pulley-blocks supported toward both extremities of said cross-arm, corresponding pulley-blocks at the base of the column, and chains or cables rove over said blocks and connected with said damper to control the closing of the damper.

In testimony whereof I have signed this specification in the presence of two subscribing witnesses.

FITZ A. KIRBY.
